WRAPPING MACHINE.

Application filed June 2, 1926. Serial No. 113,270.

This invention relates to wrapping machines and has particular reference to machines which wrap soft articles such as loaves of bread or cake.

5 In machines of such general type as illustrated in Letters Patent No. 1,412,754, granted April 11, 1922, to Sévigné & Arnold, the loaves travel down an inclined gravity slideway along one side of the machine frame, onto a horizontal plate or base member leading in to the machine, said base member being slotted for the passage of an endless series of pushers each of which is designed to push a loaf in to position to be operated upon by wrapping mechanism. The said slideway and base member are at an angle to each other, the latter having side walls to guide the loaves as they are pushed in.

20 In machines of this character, it sometimes happens that a loaf arrives from the slideway on the outer portion of the base member of the passageway leading in to the machine, more or less askew, so that when a pusher 25 engages such loaf and starts it along said passageway, the forward end of the loaf contacts with the apex of the angle where the slideway joins the said passageway. The result is that the continued movement of the pusher crushes the loaf. Then it becomes necessary to stop the machine, either manually or automatically, to remove the damaged article. This adds to the expense of employing such wrapping machines because of not 30 only the loss of some damaged articles but also the time required to remove such articles and start the machine again.

The object of the present invention is to provide such machines with means which will 40 automatically prevent the stoppage of, and damage to, articles on their way from the slideway or first portion of the angular passageway to the second portion or guideway along which the pushers travel. In accordance with said invention, the said means comprises a wall member at the apex of the angle, which wall member travels faster than the speed of advance of a pusher, so as to draw a loaf that is somewhat askew away 45 from the pusher and start it correctly along the guideway in to the machine.

50 Of the accompanying drawings:—

Figure 1 is a perspective view of so much

of the machine as is necessary to an understanding of the present invention.

55

Figure 2 is a diagrammatic plan view of a modification in structure.

Referring first to Figure 1, a portion of the frame of the machine is indicated at 40. At 42 and 43 are represented the lower end portions of the inclined gravity slideway for the loaves. Normally each loaf arrives against a stop wall 44 at the far side of the base member 45 of the guideway along which the loaves are pushed in to the machine to position to be assembled with wrapping paper. The inner side of said guideway consists of a wall plate 46. One of series of pushers 48 is illustrated. Said series of pushers are carried by an endless chain 49 carried by 70 sprockets one of which is illustrated as carried by a driven shaft 51. As so far described, the parts are supposed to be the same as the similarly indicated parts in Letters Patent No. 1,412,754 hereinbefore referred to. Reference letters instead of numerals are employed herein to designate the features of the present invention.

75

Carried by the shaft 51 is a pulley *a* connected by a belt *b* with a small pulley *c* secured to the lower end of a vertical spindle *d* suitably mounted in the frame of the machine and carrying a roll or disk *e* having a peripheral portion *f* of rubber or other suitable friction material. The said roll is so located that its periphery forms a wall member at the apex of the angle between the two portions of the passageway for the loaves, and said roll is driven at a speed that causes its periphery to travel faster than the speed of movement of the pusher 48. Such relationship of speed is indicated by the relative proportions of the pulleys illustrated.

80

85

90

95

In operation, assuming that a loaf *x* sliding down the rods 42 between the side bars 43 arrives on the base 45 not squared up against the stop wall 44 but somewhat askew as illustrated by the full lines in Figure 1, then the moment that a pusher 48 engages its rear end its front end is moved against the periphery of the roll *e* which latter, rotating at sufficient speed in the direction of the arrow, swings the front end of the loaf to or toward the dotted line position so that the pusher can cause it to travel smoothly

100

105

along between the walls 44, 46, and in to be wrapped.

Instead of employing a roll the periphery of which acts on the loaf as described, we 5 may employ a belt as indicated diagrammatically at *g* in Figure 2. Such belt is illustrated as extending around the roll *e* and around pulleys *h*, *h*¹, *h*², so that such belt may not only act in the same manner as has 10 been described, but may also act on one end of a loaf *x* near the lower end of the slide way 42 to increase the tendency of said loaf to reach the stop wall 44, and may also act 15 on the side of a loaf *x* entering the machine to guide it against the wall plate 46.

Having now described our invention, we claim:

1. In a wrapping machine having an angular passageway for the articles to be wrapped, a travelling wall member at the 20 inner apex of the angular passageway to facilitate movement of the articles past said angle, and means for causing said articles to move singly toward and past said travelling wall member.

2. In a wrapping machine having an angular passageway for the articles to be wrapped, a travelling wall member at the 25

inner apex of the angular passageway, and means for pushing the articles along through 30 the second portion of said angular passageway.

3. In a wrapping machine having an angular passageway for the articles to be wrapped, a travelling wall member at the 35 apex of the angle, and means for pushing the articles along singly through the second portion of said angular passageway to start it in a different direction of movement, means being provided for causing said travelling wall member to move at a speed higher 40 than the speed of movement of the pushing means.

4. In a machine having a guideway and 45 means for pushing articles along said guideway, an inclined slideway at an angle to the said guideway for delivering articles onto the said guideway, and a travelling friction member in position to straighten out an article that arrives askew on the said guideway.

In testimony whereof we have affixed our signatures.

HENRI A. SÉVIGNÉ.
EDMOND E. POULIN.
